[57] **CLAIM**

The ornamental design for a self standing shelving with sloped shelves, as shown and described.

DESCRIPTION

FIG. 1 is a perspective view of the self standing shelving with sloped shelves according to the present invention;

FIG. 2 is an elevational view of one end of the self standing shelving with sloped shelves, the other end being identical thereto;

FIG. 3 is an elevational view of one side of the self standing shelving with sloped shelves, the other side being identical thereto; and,

FIG. 4 is a top plan view of the self standing shelving with sloped shelves of the present invention.

Fig. 1.

Fig. 2.

Fig. 3.

Fig. 4.
